RADIO SIGNALING SYSTEM

Arthur V. Loughren, Moorestown, and Jerome C. Smith, Merchantville, N. J., assignors to Radio Corporation of America, a corporation of Delaware

Application June 30, 1933, Serial No. 678,406

16 Claims. (Cl. 179—171)

The present invention relates to radio signaling systems, and more particularly to high frequency regenerative electronic tube amplifier and oscillator systems wherein tuned high frequency circuits are employed for selective signal transmission and the generation of oscillations in connection with electric discharge amplifier devices or electronic tubes.

In the usual high frequency amplifier of the tuned radio frequency type, it is known that the selectivity in the broadcast band, for example, is greater for lower frequency signals than for higher frequency signals. To correct this operating characteristic in signaling systems wherein a more uniform frequency characteristic is desired, regeneration may be provided in connection with certain of the tuned circuits, as shown, for example, by Landon U. S. Patent 1,702,445, wherein a tuned neutralized radio frequency amplifier is provided with controlled regeneration means for increasing the selectivity and the general operating efficiency of such a system. In the system disclosed in the Landon patent, neutralization is provided in each amplifier stage, and regeneration is obtained by means of auxiliary electric discharge devices and associated circuits, for each stage.

The use of controlled regeneration, particularly for increasing the selectivity throughout certain operating ranges of a tuned radio frequency signaling system, or generally for producing controlled oscillations in a tuned circuit, is desirable, as was recognized by Landon, and has been indicated by subsequent developments in the art.

It is, therefore, an object of the present invention to provide an improved controlled regenerative amplifier system which obviates certain disadvantages of systems of that character heretofore known, such as circuit complications and an additional electric discharge device or tube requirement, or critical or unstable operating characteristics.

The patent to Landon, above referred to, also discloses the application of regeneration to a plurality of amplifier stages in what may be termed a "multiple regeneration" system, and it is a further object of the present invention to provide an improved and simplified regeneration system of that character, which is readily adapted for application to a plurality of amplifier stages.

In a tuned radio frequency amplifier, which represents any amplifier to which the advantages of regeneration may be applied and the present preferred system to which the invention is readily applicable, the selectivity throughout a certain

frequency range, such as the broadcast receiving band referred to, may vary greatly. In the broadcast band, as pointed out, the selectivity at the low frequency end of the range, for example at 600 kc. is much greater than at the high frequency end of the range, for example at 1400 kc.

It is, therefore, a further object of the present invention to provide a tuned high frequency amplifier of the character above referred to that shall provide, economically and by simple means, substantially the same desirable selectivity at the high frequency end of the tuning range as it does at the low frequency end of the tuning range.

It is also desirable, in certain amplifying systems, to control the signal output of an amplifier stage and, accordingly, it is a still further object of the present invention to provide an amplifier stage wherein controlled regeneration may be applied to increase the operating efficiency thereof, and independently of the controlled regeneration, the signal transmission efficiency or gain of the stage may be controlled.

The gain control feature above noted is desirable not only in signal amplifiers and the like, but in other electric discharge amplifier circuits wherein controlled regeneration may be utilized, such as in an oscillator or oscillation generator circuits, for example. It is, therefore, a further object of the present invention to provide controlled regeneration and amplification control in an improved oscillator or signal generator system.

In one embodiment of the invention, in connection with a radio frequency amplifier, each stage thereof is isolated by suitable and substantially complete shielding, and then an appropriate amount of regeneration is introduced into each tuned circuit to produce the desired regeneration effect. If the regeneration varies with the signal frequency in the proper manner, selectivity may be made equally good at all points in the range to be covered by the amplifier system. Resulting variations in the sensitivity of such a system, if any, may be compensated for by proper design of the interstage coupling means.

In accordance with the invention, in each regenerated shielded amplifier stage, an electron discharge device of the high gain type, having suitable electrode elements, is employed in conjunction with a feed-back circuit, whereby the device may function to provide an effective amplifier and electrically coupled regeneration means.

Instead of the additional regeneration tube heretofore considered necessary, or complicated regeneration circuits, a simple feed-back circuit

is employed in conjunction with an electron discharge device of the above type, such as an electron discharge device of the type known as a radio frequency pentode amplifier, having in addition to an electron emitting cathode and an anode, three other electrodes one of which is a screen grid, another of which is a control grid, and with a fifth element adapted to provide an anode and having a certain mutual conductance with respect to the control grid. The feed-back or regeneration circuit is provided in connection with this electrode and may then be so designed that its regeneration control upon the system may be in a direction to emphasize a desired end of the signal frequency range whereby substantially constant selectivity may be maintained.

The invention will, however, be better understood from the following description when considered in connection with the accompanying drawing, and its scope will be pointed out in the appended claims.

In the drawing,

Fig. 1 is a schematic wiring diagram illustrating a tuned high frequency amplifier stage embodying the invention;

Fig. 2 is a similar wiring diagram showing the application of the invention to a multi-stage tuned high frequency amplifier in a modification of the circuit of Fig. 1; and

Fig. 3 is a schematic wiring diagram of a further modification of the circuit of Fig. 1 to provide a controlled oscillator.

Referring to Fig. 1, 5 indicates a shielded, tuned, radio or high frequency amplifier stage connected with a source of signals such as output terminals 6 of a preceding amplifier or signal source indicated at 1, and having output terminals 8 connected with a load or utilization device, such as a succeeding amplifier stage indicated at 9.

In accordance with the invention, a single electric discharge device or electronic tube 10 is employed in the amplifier stage 5 and is so arranged in circuit between the terminals 6 and 8 that it may provide not only substantially uniform frequency band amplification in the signal channel in which the stage 5 is connected, but controlled regeneration for increasing the efficiency of the stage.

50 In the present example, the device 10 is of the five electrode type having, in addition to the usual cathode or electron emitting element 11, a control grid 12, a screen electrode 13, an anode 14, and a space charge grid 15 located between the cathode 11 and the control grid 12. This may be a type of radio tube known as a pentode, as hereinbefore described.

Pentode tubes are well known and are described on page 5 of the publication The RCA Radiotron—Cunningham Radio Tube Manual, Technical Series No. RC-11.

As referred to in the above manual, the pentode tube is provided with three electrodes between the cathode and the anode, these electrodes being nominally a control grid, a screen grid, and a suppressor grid in that order preceding from the cathode to the anode. The suppressor grid is therefore the grid adjacent to the anode and, as is well known, is connected with the cathode for the suppression of secondary emission.

In the present system the electrode 13 is that grid which is normally utilized as a suppressor grid and in the drawing occupies the position of the usual suppressor grid. However, in the present example the electrode 13 is utilized as a

screen for the anode. A pentode type of tube is therefore particularly well adapted for use in a system embodying the invention.

As is known in the art, the space charge grid 15 may be employed for the purpose of increasing the mutual conductance of the device. In accordance with the invention, however, an important additional use is made of this grid, namely as a source of energy for regeneration purposes. If, as is contemplated, the device 10 is so designed that the anode 14 is well shielded by the screen grid 13 from the remaining elements of the device, then no reaction from succeeding amplifier stages, such as the stage 9, can be fed back into the stage 5 to interfere with any condition of regeneration which may be established in the stage 5.

In carrying the above described system into effect in an amplifier stage such as that of the present example, the control grid 12 and a suitable electrode to be employed for regeneration purposes, such as the space charge grid 15, are electrically coupled whereby energy may be supplied from the one to the other. In the present example, the control grid 12 is connected with a tuned input circuit 16 comprising a variable tuning capacitor 17 connected in shunt relation to a winding 18 of an input coupling transformer 19 which is connected with the terminals 6 as the signal source.

The grid or input winding 18 is inductively coupled, as indicated by the arrow, with a regeneration or feed-back winding 20, connected with the space charge grid 15 in a regenerative plate or feed-back circuit 21.

Through the output terminals 8, the anode 14 is connected with an output or load circuit 22, in which is included a coupling device 23 for the utilization device or stage 9. Operating current at suitable potentials for the device 10 is provided from a source indicated by a pair of supply terminals 24. A potential divider means 25 is connected in shunt with said terminals and suitable connection with the various electrodes of the device for applying thereto proper operating potentials is made at various points thereon, as indicated.

In the present example, the cathode 11 is connected with a tap 26 which is more positive than a tap 27 for the control grid 12 and its input or grid circuit 16 which, as indicated at 28, is operated at ground potential. The tap points 29 and 30, for the space charge grid or regeneration anode 15 and the main anode 14, respectively, provide potentials which are more positive than the cathode. The screen grid 13 is operated also at a positive potential which is preferably variable, being connected to the variable tap point 31 through a supply lead 32. Suitable bypass capacitors indicated at 33 are provided between the various circuits and cathode to prevent undesired coupling through the supply source.

In the present embodiment of the invention, the inner or first grid 15, normally known as a space charge grid, is utilized as a regeneration plate electrode and is connected with a potential source more positive than the cathode, as above described. The feed-back coupling means, which in the present example is the winding 20, serves to supply energy to the input circuit 16 through its coupling with the coil 18.

It has been found that this feed-back arrangement is substantially independent of the operation of the device as a signal amplifier and that the amplified signal output through the circuit 75

22 from the main output anode 14 may be varied also, independently, by variation of the potential on the screen grid 13 by adjustment of the variable contact 31.

5 The combination of regeneration in the input circuit and independent control of the amplifier gain or output signal level with a single electric discharge device for each stage, permits an improved control of the gain and an improved operating efficiency to be obtained in a radio receiving system or other signaling apparatus embodying high frequency amplifiers of the electric discharge type.

10 In this embodiment of the invention also, the second or middle grid is utilized as the control grid, while the outer grid functions as a screen and gain controlling electrode or grid. It will be noted that the first or space charge grid, as a regeneration plate electrode, as above mentioned, 15 is electrostatically shielded from the main output anode 14 by the screen grid structure. However, while the transductance of the device 10 is, therefore, variable through variation of the controlling potential on the screen or outer grid 13, as above described, at the same time, the transductance of the device through the space charge grid or regeneration anode 15 is substantially independent of the control of the transductance effected by the screen grid 13.

20 It has been found that in case that the regeneration anode may draw an excessive current, then such current may be controlled or prevented from reaching excessively high values by the insertion of an impedance in circuit therewith as herein-after described.

25 Referring now to Fig. 2, in which an amplifier such as that described in conjunction with Fig. 1 is utilized in a receiving system high frequency signal channel in multiple, the advantages of a control system above mentioned may be more readily appreciated.

30 In the receiving system shown, a high frequency, tuned, multi-stage amplifier is provided, embodying two cascade connected shielded stages 35 each provided with a single electric discharge amplifier 37 and 38 of the multiple grid type providing controlled regenerative amplification and gain like that of the amplifier shown in Fig. 1. The circuits employed are substantially like that 35 shown in Fig. 1 and differ therefrom only to the extent that the circuits are adapted for multiple control of gain and of bias, together with controlled regeneration anode current, and further, with an electrode arrangement above mentioned, 40 in which the first or inner grid is utilized as a control grid.

35 Each of the electric discharge devices 37 and 38, is of the multiple grid type, having a heated cathode 39, a first or inner grid 40, a second grid 41, and a third or outer grid 42 adjacent to an output anode 43. Since the stages 35 are identical in circuit arrangement and construction, the same reference numerals are otherwise applied to 45 each stage and to the circuit and electrode elements therein.

40 The tubes shown may be the usual pentode type of tube wherein the grids 42 are normally utilized as suppressor grids while the grids 41 are utilized 50 as screen grids.

45 Each of the devices 37 and 38 in the stages 35, is provided with a tuned input circuit indicated at 44 in connection with the inner or first grid 40. A suitable feed-back coupling means 55 or coupling coil is associated with the tuning

inductance 46 for the input or grid circuit 44 and is provided with operating anode current through a resistor 47 in connection with a high potential supply lead 48.

5 The low potential side of the supply circuit is indicated at 49 and is the ground or low potential lead for the receiving channel and system. The cathode 39 is returned to this lead through a self bias resistor 50, while the input circuit 44 is returned directly thereto through the lead 51 whereby self-bias grid potentials are provided for the control grid 40 from the resistor 50.

10 The output anode 43 for the device 38 is connected with a succeeding stage or utilization device through an output circuit 52 in which is shown an interstage coupling means comprising two windings 53 and 54, providing inductive and capacitive coupling, respectively, with the input circuit 44 of the succeeding stage as shown. Any other suitable coupling means may be employed which provides for substantially uniform signal transfer over the frequency operating range of the amplifier.

15 The second of the two stages shown is provided with an output circuit 55 which may be connected with any suitable coupling means like that for the preceding stage. Suitable bypass capacitors indicated at 56 are provided in connection with the cathode, for the regeneration and input circuits and also for the outer or screen grid 42 of each of the devices 37 and 38. The latter grids receive operating and control potentials through supply leads 57 from the variable contacts 58 of separate potentiometer means 59, each connected across the potential supply leads 48 and 49 in parallel.

20 The variable contacts 58 of the potentiometer devices 59 are also connected for simultaneous gang operation as indicated by the dotted connection 60 and the operating knob 61, whereby 25 the gain or signal amplitude for each of the stages 35 may simultaneously be controlled.

25 In this embodiment of the invention the series resistor 47 in the regeneration anode circuit serves to prevent the regeneration current from rising 30 when the screen grid potentials are reduced below a predetermined value by operation of the potentiometer contacts 58. This is for the reason that as the screen grid potential is reduced, the electrons from the cathode 39 tend to travel to the 35 second grid or regeneration anode 41 instead of to the main or output anode 43, unless the regeneration circuit is protected by a series impedance such as provided by the resistor 47 in the circuit of the present example.

30 In the circuit of the present example, furthermore, the second grid is now the regeneration anode and the first grid is the control grid. The second grid, therefore, is operated preferably at a positive potential somewhat less than the main 35 anode potential. This potential may be in the order of or greater than that applied to the screen grid 42. The impedance or resistor 47 should provide a potential drop which is relatively high compared with the internal drop in the tube 40 or electric discharge device itself, so that the impedance or resistor 47 serves effectively to control the regeneration current as the screen grid potential is varied.

35 The screen or outer grid potential is variable 45 through the operation of the potentiometer means and is, generally, positive with respect to the cathode in order to maintain the mutual conductance of the electric discharge device at a high value, while at the same time providing a shield.

ing structure between the main output anode 43 and the auxiliary or regeneration anode means provided with the grid 41.

The mutual conductance or trans-conductance of the second grid 41 is less than that of the first grid 40 so that in the circuit of the present example, as distinguished from that shown in Fig. 1, the coupling for regeneration purposes with the input or grid circuit may be increased without overloading the regeneration circuit. This may be accomplished because of the higher impedance of the second grid 41 in the present type electric discharge devices available, which impedance may be of the order of 40,000 ohms as compared with the impedance of the first grid of approximately 1000 ohms with respect to the cathode.

Furthermore, with this circuit arrangement, the normal current flow to the first grid 40 may be of the order of two to three milliamperes as compared to twenty to thirty milliamperes for the circuit of Fig. 1, wherein the first grid is utilized as the regeneration anode.

In either embodiment of the invention, however, it will be seen that the electric discharge amplifier device employs a plurality of grid electrodes in addition to the usual anode and cathode, and that one of the grid electrodes serves as a screen grid structure between the main output anode and the auxiliary regeneration anode provided by another of the grid electrodes, while a third grid electrode is employed as a control grid for the amplifier device.

A regeneration coupling means is provided between the auxiliary anode electrode and the input circuit or control grid and independently of the regeneration adjustment the signal output or gain of the stage is then adjustable by varying the potential applied to the screen electrode structure.

In a cascade amplifier for the high frequency receiving circuit of a radio receiver, a relatively high gain per stage is effected and the regeneration effect and the resulting selectivity may remain substantially constant while the overall gain may be controlled simultaneously in each stage as shown. An impedance element in the regeneration anode circuit effectively maintains a substantially constant mutual conductance at substantially all control positions of the gain control means.

In the system of the present example the first amplifier stage 35 is supplied with signal energy through any suitable means such as a first stage amplifier device 62 which is coupled through a suitable tuned input circuit 63 and coupling means 64 of a signal collecting means indicated by an antenna 65 and a ground connection thereto 66, the latter being a continuation of and connected with the low potential lead 49.

The amplifier device 62 may be of any suitable type and is in the present example provided with a cathode 67 having a self-bias resistor 68 in circuit therewith, a control grid 69 connected with the input circuit 63, a screen grid 70 which receives operating potential from a tap 71 on the potentiometer 59 for the first amplifier stage 35 through a supply lead 72 and which is further provided with an output anode 73 also connected through an output 74 with the high potential supply lead 48.

In the output circuit is provided a suitable coupling means with the first output stage 35, and in the present example this coupling means 75 is provided by an electromagnetic coupling wind-

ing 53 associated with the input circuit inductance 46 and an electrostatic coupling winding 54 also associated therewith. As hereinbefore pointed out, this coupling means is arranged in any suitable manner to provide substantially uniform transfer of energy throughout the signal range over which the amplifier is designed to operate.

It will be appreciated that in case further controlled regeneration and gain may be required in the system, further stages may be provided like those shown at 35, and the input amplifier 62 may, under certain operating conditions, be arranged in the same manner as the succeeding stages. The manner of coupling in operation is obvious from the description of the two stages as shown and involves merely a duplication of either of the stages shown at 35 together with an additional control or multiple connection for the control grid of the additional stage.

Likewise, other suitable electric discharge devices of the multiple electrode type may be employed in each amplifier stage, and the invention is, therefore, not limited to the use of a pentode type of amplifier. Any amplifier having the electrodes as described hereinbefore may be employed.

Therefore a system embodying the invention may have the advantage of high selectivity and gain with controllable signal output adapted for multiple stage operation without effecting the regeneration or selectivity and without involving the use of additional electric discharge devices for that purpose.

Referring now to Fig. 3, the controlled regeneration may be applied to an oscillator having a pentode device 75 having a cathode 76 of the heated type in the present example, a control grid 77, a main output anode electrode 78, a shielding electrode or screen 79 surrounding the anode electrode 78, and isolating it from the remainder of the electrodes in the device, and an additional grid electrode 80 which in the present example is a second grid.

As shown in Fig. 3, this embodiment of the invention employs the second grid 80 as an auxiliary or regeneration anode, and is connected through a coupling condenser 81 to one end 82 of an oscillatory circuit 83, while the opposite terminal 84 thereof is connected to the control grid 77 through the usual grid leak and condenser combination indicated at 85. The anode circuit for the grid electrode 80 is connected with any suitable source of potential through a lead 86, in which is located a high frequency choke coil 87 providing the coupling impedance for the coupling condenser 81.

The oscillator circuit is provided with the usual tapped grid-plate inductance 88 which is connected to a cathode return lead 89 through a lead 90.

The main output anode circuit for the anode 78 is indicated at 91 and output signals are available between the lead 91 and the ground lead 89 in the circuit of the present example as output leads. It will be noted that the screen grid structure 79 effectively surrounds the output anode 78 and is connected to the cathode lead 89 through a supply lead 92 and a variable source of biasing potentials provided by any suitable means, such as a battery 93 and a variable potentiometer device 94 connected in shunt thereto with the variable contact 95 thereof connected with the supply lead 92. The battery is provided with a center tap 96 which is connected 76

to the cathode return lead 89 through a grounded return lead 97 whereby as the potentiometer contact 95 is moved between the extreme limits or terminal ends of the potentiometer device, 5 suitable negative and positive potential may be applied to the screen grid structure to control the oscillation output of the oscillator between wide limits.

It will further be noted that the oscillator is 10 provided with a shield enclosure indicated at 98, which is also connected to the cathode return lead 89 and is arranged to cooperate, as indicated, with the screen grid structure 79 to electrically isolate the output anode and the output circuit 15 91 therefrom from the remaining electrodes of the electric discharge device and the oscillator circuit 83. This may be arranged in any suitable manner such as by having the shield 98 terminate adjacent to the device 75 and in direct association 20 with the screen structure 79 as indicated diagrammatically in the drawing.

With the oscillator circuit or oscillator generator system arranged as shown, the oscillation frequency established in the generator circuit 83 25 is substantially independent of the oscillation signal output circuit 91 and the amplitude of the oscillations delivered to the circuit 91 may be controlled between wide limits without affecting the frequency adjustment of the circuit 83 for 30 which a usual shunt condenser 99 in conjunction with the coil 88 is provided.

As the operation of the oscillation generators is known and understood, further description of the operation is believed to be unnecessary. 35 However, it should be pointed out that in providing an oscillator in accordance with the invention, the output anode should be effectively electrically shielded from the remaining elements of the oscillator device employed, and that the screen grid structure should effectively be enclosed between the anode electrode, through which oscillations are produced, and the signal output anode.

In this connection, therefore, it is preferable to employ a multiple grid electrode electric discharge device and to employ the first or inner grid as the control grid, while the next adjacent or second grid is utilized as the feed-back or oscillation anode, and between these two electrodes any suitable oscillation generator circuit 40 may be provided. By controlling the potential applied to the screen grid structure associated with the output anode electrode, the signal amplitude for energy may effectively be controlled between wide limits without affecting the frequency setting of the oscillation generator circuit.

It should further be noted that in providing the feed-back coupling, a fixed coupling means is employed. Any other coupling means may, however, be employed, as hereinbefore explained.

A fixed coupling has the advantage in certain amplifiers, such as a tuned high frequency amplifier shown in Fig. 1, that a sufficient amount of regeneration is obtained at or in the higher 45 frequency end of the tuning or operating range of the system through a proper degree of coupling to provide a desired selectivity effect in this range where the selectivity is ordinarily lower than at or in the low frequency end of the tuning or operating range of the system.

The regeneration effect is permitted by the fixed coupling to decrease with a decrease in frequency so that at or in the low frequency end of the tuning range substantially no regeneration 50 is obtained. Since the selectivity is ordinarily as

desired in the low frequency end of the range, the selectivity of the system is thereby rendered substantially flat or uniform throughout the tuning or operating range.

Other embodiments of the invention will readily be apparent to those skilled in the art and, therefore, the invention is not limited to the particular embodiments shown and described herein, but only by the prior art and the scope of the appended claims.

We claim as our invention:

1. An electric discharge amplifier including in combination, an electric discharge device having a cathode, a main output anode and a plurality of grid electrodes interposed therebetween, a signal input circuit connected between the cathode and one of said grid electrodes, means providing a regenerative feed-back coupling between another of said grid electrodes and said input circuit, means for applying a positive potential with respect to cathode on said last-named electrode, means for applying a variable controlling potential to a third grid electrode more adjacent to the main output anode, and a signal output circuit connected with said output anode. 20

2. In a radio signaling system, an electric discharge amplifying stage comprising an electric discharge amplifier device having a cathode, an anode, a control grid, a second grid adjacent thereto and a screen grid adjacent to the anode, a signal input circuit connected with the control grid, a signal output circuit connected with the anode, means providing a regenerative electrical coupling between the second grid and said input circuit, and means for applying operating potentials to said electrodes including a positive potential on said second grid electrode less than the anode potential and a variable potential on said screen grid. 30

3. In a radio signaling system, an electric discharge amplifying stage comprising an electric discharge amplifier device having a cathode, an anode, a control grid, a space charge grid and a screen grid adjacent to the anode, a signal input circuit connected with the control grid, a signal output circuit connected with the anode, means providing a regenerative electrical coupling between the space charge grid and said input circuit, means for applying a positive operating potential with respect to cathode to said space charge grid, and means for applying a variable positive potential to said screen grid. 40

4. An electric signal amplifier comprising in combination, an electronic tube amplifier device having a signal input electrode and a signal output electrode, a screen electrode for said output electrode and an electrode providing a regeneration anode, means providing a regenerative electrical coupling between said regeneration anode and the first named electrode, and means connected with the screen electrode for applying a variable potential thereto whereby the signal output from said output electrode may be varied independently of said electrical coupling. 50

5. In a radio signaling system, a regenerative electric discharge amplifier including a signal amplifier device having a cathode, an anode, a control grid more adjacent to the cathode, a grid more adjacent to the anode and an additional electrode, a signal input grid circuit connected between said control grid and the cathode, said additional electrode having a predetermined mutual conductance with respect to the control grid electrically coupled to said grid circuit to supply feed-back electrical energy thereto for 55 70 75

regeneration below the point of oscillation, means in circuit with said additional electrode for limiting current flow thereto, and means for applying to the grid more adjacent to the anode a variable potential for controlling the mutual conductance of said device and the signal flow through said amplifier.

6. A radio signaling system including in combination, a plurality of cascade connected electric discharge amplifier stages, each of said stages being electrically shielded and including an electric discharge amplifier device having a signal input circuit and a signal output circuit, means for coupling an electrode of said device other than an output electrode with said input circuit to provide regeneration, means for applying a varying gain controlling potential to another electrode of said device, and means for simultaneously operating each of said last named means in each stage.

7. A radio signaling system including in combination, a plurality of cascade connected amplifier stages, at least one of which is shielded from another and each of which comprises an electric discharge amplifier device having a cathode and a signal input electrode, a signal output electrode, a screen electrode adjacent thereto, and an additional electrode, means providing a regenerative electrical coupling between said additional electrode and the input electrode at signal frequencies, current limiting means in circuit with said additional electrode, means for supplying operating potentials to said screen electrodes, and means for simultaneously varying said last named potentials in each stage.

8. A radio signaling system including in combination, a plurality of cascade connected amplifier stages, at least one of which is shielded from another and each of which comprises an electric discharge amplifier device having a cathode, a signal input electrode, a signal output electrode, a screen electrode therefor and an additional electrode, means providing a regenerative electrical coupling between said additional electrode and the input electrode at signal frequencies, current limiting means in circuit with said additional electrode, means for supplying operating potentials to said screen electrodes, and means for simultaneously varying said potentials in each stage, said last named means comprising a potentiometer device connected with said supply means and having a variable tap point connected with one of said screen electrodes.

9. The combination with an electron discharge device having a control grid, a main anode and an auxiliary anode, of a signal input grid circuit connected to said grid, means for rendering the transductance between the auxiliary anode and the control grid substantially constant in response to variations in the transductance between the control grid and the main anode, said means including a unitary screen grid structure interposed between said anodes and between the main anode and the control grid, means for applying a variable positive potential to the screen grid structure, and means for applying substantially a constant current to the auxiliary anode.

10. In a tuned high frequency amplifier, the combination of an electronic tube amplifier device having a signal input electrode and a signal output electrode, a screen electrode for said output electrode and an auxiliary electrode, means providing a predetermined regeneration coupling between said auxiliary electrode and said first

named electrode whereby substantially uniform selectivity is provided by said amplifier throughout the tuning range thereof, and means connected to the screen electrode for applying a variable potential thereto, whereby the signal output from said output electrode may be varied independently of said electrical coupling.

11. In a radio signaling system, an electric discharge amplifying stage comprising an electric discharge amplifier device having a cathode, an anode, a control grid, a screen grid and a suppressor grid, a signal input circuit connected with the control grid, a signal output circuit connected with the anode, means providing a regenerative electrical coupling between the screen grid and said input circuit, means for applying a positive operating potential with respect to cathode to said screen grid, and means for applying a variable controlling potential to the suppressor grid.

12. In an electric discharge amplifier, the combination of an electric discharge device having a cathode, an anode, a control grid, a grid structure adjacent to the anode and an auxiliary anode electrode interposed between said grid structure and the cathode, means providing regenerative feed-back coupling below the point of oscillation between the control grid and the auxiliary anode electrode, a signal input grid circuit connected with said control grid, an output circuit connected with said first named anode, and means for applying a variable potential to the said grid structure whereby the electrical output through said output circuit may independently be varied.

13. A radio signaling system including in combination, a plurality of cascade connected electric discharge amplifier stages, each of said stages being electrically shielded and including an electric discharge amplifier device having a signal input circuit and a signal output circuit, means for coupling an electrode of said device other than an output electrode with said input circuit to provide regeneration, and means for applying a variable gain controlling potential to another electrode of said device.

14. An electric tube amplifier system including in combination, a signal input grid circuit, a regenerative feed-back circuit coupled to said input circuit, a suppressor grid circuit, and means for supplying a variable controlling potential to said suppressor grid circuit.

15. In an amplifier system, an electron discharge amplifier circuit comprising in combination, a tunable signal input grid circuit, a screen grid potential supply circuit regeneratively coupled to said grid circuit, a suppressor grid potential supply circuit, means in said last named circuit for varying the potential of said circuit, and a signal output anode circuit.

16. In an amplifier system, the combination with an electron discharge device having a cathode, an anode, a control grid, a screen grid, and a suppressor grid between said cathode and anode, of a signal input grid circuit connected with said control grid, means including said input grid circuit for regeneratively coupling said control grid and screen grid, a signal output circuit connected with the anode, and means for variably controlling a potential on said suppressor grid to variably control the amplitude of signals applied to said output circuit.
